ADOLPH RYDQUIST, OF ROCHESTER, NEW YORK.

CAN-OPENING MACHINE.

Application filed September 25, 1922. Serial No. 590,286.

My present invention relates to can opening machines and it has for its object to provide a simple, compact and convenient machine of this character that can be rapidly operated and into which the cans can be inserted with ease. The improvements are directed in part toward cutting devices for removing a can top in such manner as to leave a neat and safe edge on the can body and toward arranging for cutting the top in either of two ways in the one machine. Other improvements relate to the manner in which the can is inserted and held in the machine or released therefrom and to these and other ends the invention resides in certain improvements and combinations of parts, all as will be hereinafter more fully described, the novel features being pointed out in the claims at the end of the specification.

20 In the drawings:

Fig. 1 is a side view of a can opening machine constructed in accordance with and illustrating one embodiment of my invention, portions of the attaching means and of the can shown in place thereon being broken away.

Fig. 2 is a front view thereof.

Fig. 3 is a top view, the handle being broken away.

Fig. 4 is a sectional view on the line 4—4 Figure 1.

Fig. 5 is a similar view with the parts in another position.

Fig. 6 is a vertical central section on the line 6—6 of Fig. 3.

Fig. 7 is a similar section with the parts in another position.

Fig. 8 is a collective view partly in section showing the relationship of the cutter and anvil while the can is being gripped or cut.

Fig. 9 is a similar view showing such relationship when the can is released.

Fig. 10 is an enlarged prospective view 45 of a part of the clutch mechanism in detail.

Fig. 11 is an enlarged fragmentary sectional view showing the manner in which the cut of one kind is made.

Fig. 12 is a similar view showing the manner in which a cut of another kind is made and

Fig. 13 is an enlarged fragmentary view

showing the top of the can partly cut in the manner of Fig. 11.

Similar reference numerals throughout the several views indicate the same parts.

The first given idea of the nature of the machine, I provide a substantially vertically disposed anvil roll which engages on the inside of the bead of the can and operates as a driving mean to rotate it. In opposition to this anvil roll is a rotary cutter that is reversible and cuts the top either at the bead or seam or just below the seam. The can is supported wholly by this cutting engagement of the two elements with the bead or seam and semi-automatic operating mechanism is provided whereby the cutter and anvil are moved relatively to each other to grip or release the can as the case may be.

Referring more particularly to the drawings 1 indicates a bracket support or casting having jaws 2 and 3 by means of which it may be clamped to the edge of a table 4 with a screw 5 or permanently secured thereto by screws inserted in the openings 6 shown in Fig. 3. An overhanging cylindrical portion 7, faced off on top at 8 has a bearing form thereon in which turns a bushing 9 disposed at a slight backward angle. Within the bushing 9 is formed an eccentric bearing in which turns a shaft 10 carrying at its lower end a projecting knurled roller 11 constituting the driving roll and anvil against which the cut is made and which cooperates with the bead of the can top as shown in Figs. 1, 11 and 12. To the upper end of the shaft 10 is pinned at 12 a crank 13 which the operator turns by means of the knob 14.

The rotary cutter wheel 15 has a cutting edge 16 having an operative relationship with the anvil roll 11 that is shown in Figs. 6 and 11. This cutting edge is in a plane at an angle to the plane of the anvil but its point of contact is in that plane and it runs around the bead or seam of the can in direct opposition to the anvil roll. I have illustrated in Figs. 11 and 12 a can bead of the usual double-seam type. The can is indicated at A and the top at B. The side wall A is turned at a and doubled on itself at a'. This doubled portion is embraced by and locked into a doubled portion b' of the top B the first fold, b, of which constitutes the rim or top of the bead. The cutting edge 16 is so arranged and

so related to the anvil 11 that it cuts only through the outer layer of the can top B near the top of the fold or seam between the folds or bends b and b' . It is an upward or slanting cut as before described and is preferably tangential to the underlying top fold a of the can wall A. The purpose of this is two-fold: first to give a tendency to lift the can top after it is severed and second to leave the opened can body with a smooth rim that will not injure the hands or prevent its use as a utensil after its contents are emptied. The angular shearing cut leaves no burr on the portion of the can top that is left locked in the seam or bead.

Regulating the above depth of cut is assisted by a V shaped roller portion 17 on the end of the cutter roll that travels against the can wall just beneath the bead. Its edge even compresses the can wall slightly or bows it inwardly as indicated at A' in the region of the shoulder B' of the can top and, acting against this shoulder, operates to lift and free the severed top so that it can be readily removed from the can with the fingers.

The cutter roll also has another V-shaped cutting edge 18 arranged above the edge 16 when 18 is inoperative as shown in Figures 6, 7 and 11. The cutting roll is reversible, however, and when it is turned end for end as in Figure 12 the cutting edge 18 pierces the can wall A just below the bead and below the shoulder B' shearing the side wall instead of the top as shown in Figure 12, if this is preferred or if the bead on the particular can being operated upon is of unusual shape or thickness or otherwise ill adapted to the cutter 16.

The inclined axis of the cutting roller is defined by a detachable stud 19 upon which it freely turns and upon which it is held only by a shoulder 20 on the supporting bracket 1 when not in use. When in operation the cutter is forced onto the stud and requires no fastening. The stud occupies a cylindrical socket 21 in the support into which it is inserted and from which it may be withdrawn by means of a head 22. Just beneath the head it is provided with an eccentric portion 23 occupying a slightly larger eccentric countersink from the mouth of the socket 21. Rotation of this stud with the fingers jams the eccentric 23 sufficiently to hold the stud in place though it can be easily released. When the stud is withdrawn the shoulder 20 cannot alone retain the cutter roll which may thus be removed and reversed.

The operative relationship of the cutter and anvil rolls is shown in Figure 8. When it is desired to insert the can these elements must be separated as shown in Figure 9. This is accomplished by rotating the bushing 9 that carries the anvil roll shaft 10 slightly from the position of Figure 8 to that of Figure 9, the shaft being eccentrically mounted in the

bushing as previously described. I effect this relative movement in a semi-automatic manner by manipulation of the crank handle 13 only through the use of a clutch mechanism that I will now describe.

On the face 8 of the support is a perforated plate 25 having an upturned marginal ear 26 constituting a stop. It is secured to the support by a clamp screw 27 occupying an arcuate slot 28 therein and which screw constitutes a second stop. Above the stop plate 25 and bearing against the same is an annular enlargement 29 on the bushing 9 constituting a clutch element. On the upper face of this clutch element is an arcuate cam tooth 30 upon which rides a gravity operated vertically disposed clutch pin 31 occupying a cavity 32 in the hub 33 of the crank 13, which hub has a bearing on the clutch element 29. When the crank 13 is turned to the right or clockwise as it normally is in cutting the can, this clutch pin 31 simply rides on the cam tooth 30 and drops off of the abrupt end face so that there is no clutch connection and the crank does not affect the position of the bushing 9 which is in the position of Figure 8. When, however, it is desired to release the can or insert a can the bushing must be rotated to the position of Figure 9 which is accomplished by reversing the crank 13 to a counterclockwise direction whereupon the clutch pin 31 will lock against the end face of the tooth 30 and carry the latter and the bushing with it.

This release of the anvil roll 11 through rotation of its bushing having been accomplished it becomes necessary to return it to the gripping position of Figure 8 to clamp the bead of the next can. I do this in the present instance through the use of a shiftable abutment 34 shown in detail in Figure 10. It has a cylindrical body portion 35 that is pivotally mounted in the clutch element 29 of the bushing and has a curved face 36 that may occupy a position concentric with the path of the clutch pin 31 as shown in Figure 4 or a cocked position in which the abutment will project into the path of the pin 31 and block it as shown in Figure 5. When the reversal of the crank and the engagement of the pin 31 with the tooth 30 rotates the bushing 9 a sufficient distance it is stopped by a laterally projecting arm 37 on the abutment 34 which arm swings in a slot 38 in the hub 33 and engages the stop screw 27 as in Figure 5. Therefore, on the initial movement of the crank to the right with the can held in place with its bead between the cutter and anvil, the clutch pin 31 will engage the abutment 34 and in this way pick up the bushing 9 for rotation with the crank which it does until the arm 37 strikes the other stop 26. This rotates the abutment 34 out of the path of the pin; the pin passes it and thereafter moves idly leaving the bushing stationary until the crank is again reversed to release the can.

I claim as my invention:

1. In a can opening machine, the combination with an anvil adapted to cooperate with the inner side of the can bead, of a detachable reversible rotary cutter having, in one position, a cutting edge adapted to travel peripherally of the bead in direct opposition to the anvil and, in the other position, a second cutting edge adapted to travel peripherally of the can just below the bead. 45
2. In a can opening machine, the combination with a support having a cylindrical socket therein provided with an eccentric portion, and an anvil mounted on the support, and adapted to cooperate with the inner side of the can bead, of a detachable stud extending through the socket and provided with an eccentric portion adapted to jam in the eccentric portion of the socket and 50 a rotary cutter detachably mounted on the stud. 55
3. In a can opening machine, the combination with a support having a cylindrical socket therein provided with an eccentric portion, and an anvil mounted on the support and adapted to cooperate with the inner side of the can bead, of a detachable portion adapted to jam in the eccentric portion of the socket and a rotary cutter detachably mounted on the projecting end of the stud, the support being provided with a shoulder for normally retaining the cutter on the stud. 60
4. In a can opening machine, the combination with a support having a bearing and a bushing rotatable in the bearing and itself provided with an eccentric bearing, of an anvil roll journalled in the bushing and adapted to travel upon one side of a can bead, a cutter on the support adapted to cooperate with the can in opposition to the anvil roller, a stop plate on the support encircling the bushing and provided with two stops, the bushing being provided with an enlargement overlying the stop plate, a crank connected to the anvil roll and having a clutch pin thereon, means on the enlarged portion of the bushing interlocking with said clutch pin only when the crank is reversed in direction to carry the anvil roll away from the cutter and a shiftable abutment pivoted on the bushing and engaging one of the stops whereby it is thrown into the path of the clutch pin by the reversal of said crank to subsequently carry the anvil roll toward the cutter when the crank is later rotated in the normal direction, said abutment being shifted back to inoperative position by engagement with the other stop during such normal movement of the crank. 65 70 75 80
